RAFTER PRINCIPALS FOR USE IN ROOFS OF LARGE SPAN

Henri Maclaine Pont, Voorburg, Netherlands

Application March 17, 1953, Serial No. 342,879

Claims priority, application Netherlands March 31, 1952

3 Claims. (Cl. 108—1)

The invention relates to a rafter principal for a roof of large span of the type described in U. S. Patent No. 2,545,556 and comprises, in combination, abutment structures at the corners of the roofed space only, flexible curved rafters, which rest on said abutment structures, meet in the top of the roof and are turned with their concave sides toward the inside, eaves-cables provided round about the roof on the level of the lower ends of said rafters, networks composed of completely flexible stretchable wire-like means provided in the roofing planes between said rafters and said eaves-cables, and a roof covering supported directly by said roofing networks. In such roof structures the danger of buckling of the rafter principals due to the expected efficient variations of the shape thereof is eliminated. However, the rafter principals must be able to take up great compressive stresses in their longitudinal direction. Moreover they must be adapted to be constructed in very great lengths.

The present invention has for its object to provide for such a roof a rafter principal of simple construction, which fulfills the above mentioned requirements. It resides in that the rafter construction consists of a rigid foot member, a rigid top member and a composite intermediate member, said intermediate member comprising layers of resilient bars, which partly overlap each other and point with their lower ends toward the outside and with their upper ends toward the inside of the rafter principal, and link members, which engage, in a manner permitting the rafter principal to take up compressive strain, with their parts turned toward the outside of said top member and the lower ends of said bars respectively, and with their parts turned toward the inside the upper ends of said bars and said foot member, respectively, the main axes of said bars and said link members enclosing acute angles. This construction makes it possible to compose the rafter construction of a great number of bars, which are easily to be manufactured and are automatically pressed one upon the other and together form in each place of the rafter principal a cross-section of sufficient area to take up the compressive strain set up in the principal, without the flexibility of the construction as a whole being unfavourably affected by the relatively large cross-sectional area thereof.

The rafter construction may be formed in various manners. Preferably the bars are solid, have a square cross-section and are of equal lengths. The link members may consist of blocks and connecting rods, said blocks being engaged by the bars and said rods being at both ends hingedly connected to said blocks.

The bars may be pre-bent according to the thrustline of the rafter construction, when the roof is in its condition of rest. In that case the bending of the rafter construction to the outside and to the inside during the movements of the roof due to the influence of the weather and the like depends on the elasticity of the bars, which then always form a rigid unit irrespective of the movements of

2

the rafter construction. Only one kind of link is then needed.

The bars may also be straight bars. In the case, however, the spaces left open between the bars, when the foot ends or other particular points of the bars follow the thrustline referred to, will have to be filled up with filling or distance blocks. Advantageously these filling or distance blocks are mounted in the interspaces near the connecting rods of the link members. In that case the said rods will have to be of various lengths. However, if the link members are made adjustable, only a few types of connecting rods are needed. Also then the variations of the form of the rafter construction owing to the varying load depend on the elasticity of the bars.

15 The construction of the rafter structure according to the invention has the advantage, that the mounting of the structure is rather simple, especially when large spans are concerned. The use of section iron and riveting and welding processes are substantially dispensed with in a 20 structure according to the invention.

The blocks of the link-members may be formed and engage each other in such a manner, that they form a continuous outer layer or an uninterrupted inner layer of the rafter structure, when the latter attains a predetermined minimally or maximally bent position, respectively, during the movements of the roof for restoring the equilibrium. These blocks then engage each other and locally enlarge the cross-sectional area of the rafter structure, so that the latter is proof against greater compressive 30 strain. These additional compression zones are not operative, when loads occur within the range, which will have to be considered in the calculation of the construction in connection with the weather statistics and the building regulations. Only, when extreme weather conditions or other catastrophes occur, will they be active.

The accompanying drawing illustrates diagrammatically and by way of example one embodiment of a rafter principal according to the invention and wherein:

Fig. 1 is a diagrammatical elevational view of a rafter 40 principal for an elastic roof of large span,

Fig. 2a on a larger scale the foot portion of said rafter principal,

Fig. 2b is on a larger scale the top portion of said rafter 45 principal, and

Fig. 3 is a cross-sectional view on line III—III in Fig. 2a.

In the drawings 1 designates a foot-member and 2 is a top-member of the rafter principal. These members 50 form the ends of the rafter principal and they are of rigid construction and may be made of cast or wrought metal. The foot-member 1 bears through a universal joint on a spherical foot 3, which bears with its spherical sole surface 4 on a surface 6 of a stationary support through balls 5. The illustrated rafter structure forms a part of an elastic roof provided with spherical foot supports as described in the copending U. S. patent application Serial No. 210,510, now Patent No. 2,705,928.

The intermediate part of the rafter structure, that is 60 the part extending between the foot-member 1 and the top-member 2, is composed of layers of bars 8 lying one beside the other. These layers overlap each other at their adjoining upper and lower ends. Thus, the bars of the first layer, which are joined at their upper ends to the top member, overlap, at their lower ends, the upper ends of the next or second layer of bars in such a manner that a link means connecting the bars of the layers, and the bars enclose acute angles. This construction follows for succeeding layers down to the lowermost layer of bars which 70 is joined to the foot member. Said bars abut with their outward and footward pointing ends against blocks 9 through interposed cross-bars 8a and they engage blocks

10 with their inward and upward pointing ends. The blocks 9 and the top-member 2 are hingedly connected with the foot-member, the blocks 10 and intermediate blocks 10a, respectively, by means of link-rods 11. To this end the link-rods 11 are pivotally connected with their outward pointing ends to the blocks 9 and the top-member 2, respectively, and with their inward pointing ends they are passed through cross-beams 12 and fixed by means of nuts 13 or they are pivotally connected to the foot-member. Each of the cross-beams engages, with a half-cylindrical surface 14, corresponding recesses of the blocks 10, 10a which are situated one beside the other. The blocks 10, 10a are slidably suspended on the bars of a next layer by means of braces 15. In the region, where the rafter principal is curved, distance-blocks 16 are provided between the bars 8. These blocks are connected to the link-rods 11 by means of braces 17. The link-rods 11 and the bars 8, which are interconnected by said rods, enclose acute angles. The bars 8 are pressed upon each other or upon the interposed blocks 16 by the weight of the roof-covering supported by the rafter principal. The blocks 9 and 10, 10a are so formed and of such dimensions, as to abut against each other or to engage each other in the manner of hooks, when, during the movements of the roof for restoring the equilibrium, the rafter principals attain the minimum or the maximum curvatures to be expected, respectively.

Each horizontal row of blocks 9 may be connected to a horizontal row of blocks 10 and a horizontal row of blocks 10a by means of two rows of link-rods 11. In

the present construction the flexibility of the rafter principal depends on the elasticity of the bars.

What I claim is:

1. A rafter structure for a roof of large span consisting of a rigid foot member, a rigid top member and a composite intermediate member disposed between the foot member and the top member, said intermediate member comprising layers of resilient bars, said layers being inclined between the top member and the foot member and pointing with their lower ends toward the outside and with their upper ends toward the inside of the curve of the rafter structure and said layers having their lower ends overlapping the upper ends of adjoining lower layers, link means connecting the uppermost layers with the top member and the lowermost layers with the foot member and connecting the lower end of an intermediate layer with the underlying upper end of an adjoining intermediate layer, the longitudinal axes of the bars of said layers and the link means enclosing acute angles.

2. A rafter structure as claimed in claim 1, wherein the link means includes blocks at the upper and lower ends of the bars and connecting rods hingedly connected at both ends to the blocks.

3. A rafter structure as claimed in claim 1, wherein distance-pieces are locally provided between the bars of adjoining layers.
